UNITED STATES PATENT OFFICE.

RUFUS A. SUMMERS, OF OPDYKE, ILLINOIS.

RAILWAY-TIE.

1,151,062.

Specification of Letters Patent. Patented Aug. 24, 1915.

Application filed November 10, 1914. Serial No. 871,310.

To all whom it may concern:

Be it known that I, RUFUS A. SUMMERS, citizen of the United States, residing at Opdyke, in the county of Jefferson and State 5 of Illinois, have invented certain new and useful Improvements in Railway-Ties, of which the following is a specification.

This invention relates to certain new and useful improvements in railway ties and has 10 as its primary object to provide a metallic tie which will be relatively light but which at the same time, will be strong, durable, and thoroughly efficient in operation, and which will be so constructed as to be possessed 15 of the resilient qualities found in the ordinary wooden tie to thus support the rails in like manner.

The invention has as a further object to 20 provide a metallic railway tie wherein the ends of the tie in use, will be capable of free vertical movement to thus give under a heavy load and wherein resilient means will be employed for holding the ends of the tie in normal position, the said means coacting 25 to maintain the rails in engagement with the tie, and being disposed to absorb the shock of a load passing over the tie.

A further object of the invention is to 30 provide a metallic railway tie of substantially skeleton construction and wherein the resilient means employed for maintaining the ends of the tie in normal position will form a closure for the tie at its upper side and will be arranged to fulcrum upon the 35 tie in such manner as to normally hold the means provided for connecting the rails with the tie in engagement with the rails.

A still further object of the invention is 40 to provide a tie of this character wherein a single resilient means will be employed for maintaining the rails in engagement with the tie and for absorbing the shock of a load passing over the tie. And the invention has as a still further object to provide a tie of 45 this character which will be simple in construction, which may be easily placed in position within the road-bed, and which will be provided with means for engagement with the rails of such character that the use 50 of spikes or other similar type of fastening devices may be dispensed with.

With these and other objects in view my

invention will be more fully described, illustrated in the accompanying drawings and then specifically pointed out in the claims 55 which are attached to and form a part of this application.

In the accompanying drawings:—Figure 1 is a perspective view of my improved tie showing the rails operatively connected therewith, the said rails being broken away, Fig. 2 is a horizontal sectional view taken through the tie and particularly illustrating the peculiar formation of the rail chairs carried by the tie as well as the clamping 60 plates employed for connecting the rails with the tie, the rails being shown in section, Fig. 3 is a transverse sectional view taken on the line 3—3 of Fig. 2, the portion of the rail shown being broken away, this 65 view particularly illustrating the manner in which the clamping plates engaging the rail engage around the rail chairs of the tie, Fig. 4 is a perspective view showing the several parts of the tie detached but in proper 70 operative position, and Fig. 5 is a transverse sectional view showing the manner in which the sections of the tie are hingedly connected with each other.

Corresponding and like parts are referred 80 to in the following description and indicated in all the views of the drawings by the same reference characters.

The body portion of my improved tie indicated at 10 in the drawings, is preferably 85 formed of suitable metal and in order that the said tie may be relatively light, it is of skeleton or channeled construction, the said tie including a bottom wall 11 and side walls 12 which extend at substantially right angles 90 to the bottom.

As best shown in Fig. 4 of the drawings, the body portion 10 of the tie is formed of hingedly connected sections 13 and 14, each of said sections, at its outer end, being laterally enlarged as at 15 to provide a tread. Preferably, the tread 15 of each of said sections is provided with an outer concave face 16 as best shown in Fig. 2 of the drawings, this construction facilitating the engagement 95 of the tie with the road-bed.

Formed within the sections 13 and 14 at the inner extremities thereof and upon opposite sides of the said sections, are verti-

cally arranged shoulders 17 and 18, each of said shoulders extending medially of the adjacent section transversely thereof and being provided with a flat end wall 19, the flat end walls of said shoulders confronting each other when the sections are operatively connected together as illustrated in Figs. 3 and 5 of the drawings.

The upper ends of the shoulders 17 and 18 terminate in spaced relation to the upper edges of the side walls 12 of the sections 13 and 14 and are preferably rounded in cross-section as shown at 20, this being for a reason which will presently appear.

15 Formed on the end wall 19 of the shoulder 18 adjacent the base of the said shoulder, is a laterally extending stud 21 which is disposed to engage within a suitable aperture 22 formed in the end wall of the shoulder 17. In this manner, the sections 13 and 14 are hingedly and detachably connected together and in order to prevent dirt or other foreign matter from gaining entrance within the tie, the bottom wall 11 of each of the 25 sections adjacent the shoulders 17 and 18, is provided with a laterally extending flange 23 disposed to overlap the adjacent portion of the bottom wall of the opposite section while oppositely disposed side walls 12 of the 30 said sections, at their inner extremities, are each provided with a similar flange 24 disposed to receive the adjacent terminal of the corresponding side wall of the opposite section.

35 From the above description, it will be seen that the body portion of my improved tie is relatively light in construction, this being a very desirable feature in a tie of this character, since the said tie may thus be readily 40 transported for use and it will be observed that when initially placing the tie within the road-bed, the sections thereof may be detached to be inserted beneath the rails from opposite sides of the road-bed and 45 thence connected by inserting the stud 21 within the aperture 22. Consequently, in the construction which I provide, I gain, in thus being able to place the tie within the road-bed, an advantage over the ordinary 50 wooden tie and shall now proceed to describe the construction whereby I attain, in my improved tie, the resilient quality disposed to cushion the load upon the tie, possessed by the ordinary wooden tie. However, 55 before proceeding with such description, it may be stated that in order that snow or water may be prevented from standing within the tie, the upper faces of the bottom walls 11 of the sections 13 and 14 60 are preferably inclined toward the outer ends of the said sections as best shown in Fig. 2 of the drawings, so that moisture will drain from within the tie.

Extending transversely above the treads 65 15 and supported by the side walls 12 are

chairs 25, the said chairs being integrally formed with the side walls while the said side walls are notched at the extremities of the chairs to provide shoulders 26 at the sides of the chairs and at the terminals 70 thereof. The chairs 25 are provided with upper flat faces 27 to receive the rails conventionally shown at 28 and are preferably, substantially semi-cylindrical in cross-section being provided with curved lower faces 75 28' which upon the inner confronting sides of the said chairs, are cut away circumferentially to provide seats 29.

As previously stated, and as illustrated in the drawings, the base flanges of the 80 rails 28 are disposed to seat upon the upper flat faces 27 of the chairs 25 and are engaged by the shoulders 26. Embracing the chairs 25 and engaging the base flanges of the rails 28, are coacting clamping plates 30 and 31, 85 the said plates being shown in detail in Fig. 4 of the drawings. More particularly, the plates 30 are each formed from a piece of suitable resilient metal and include outwardly diverging and longitudinally extending flanges 32 and 33, the flange 33 being preferably wider than the flange 32. As best shown in Fig. 2 of the drawings, the flange 32 of each of said plates is disposed to engage over the adjacent side of the base 90 flange of one of the rails 28 with the flange 33 embracing the adjacent chair 25 and disposed within the seat 29 thereof. The clamping members 31 are also each preferably formed from a suitable piece of resilient metal and each of said members at one extremity thereof, is provided with a terminal longitudinally extending flange 34 disposed to engage over the base flange of the adjacent rail upon the outer side thereof 100 and extending from the said flange is a resilient longitudinally curved arm 35 which fits around the curved face 28' of the adjacent chair to extend over and engage the flange 33 of the adjacent clamping plate 30, 105 it being observed upon reference to Fig. 2 of the drawings, that the flanges 33 of the plates 30 are transversely curved to conform to the curvature of the adjacent walls of the seats 29 as well as the curvature of the 110 arms 35 so that the said arms will bear against the said flanges throughout their entire length.

The arms 35 of the members 31 are preferably of such length as to extend at the 120 adjacent extremities thereof above the upper edges of the side walls 12 of the tie and terminate in longitudinally extending and laterally disposed hooks or flanges 36, the free extremities of which are arranged to 125 project downwardly toward the tie. Engaging the said hooks is a combined locking and closure member 37. The closure plate 37 is preferably formed from a single piece of relatively heavy resilient metal, and, as 130

shown in Fig. 4 of the drawings, is longitudinally bowed. Formed on the member 37 at the extremities thereof, are transversely extending hooks or seats 38 which 5 are disposed to receive the free terminals of the hooks 36, the member 37 being of a length to extend between the said hooks and being of a width to fit snugly between the side walls 12 of the tie to close the tie upon 10 the upper side thereof.

In assembling the several parts of the tie, the sections 13 and 14 thereof, are operatively connected in the manner heretofore described and the clamping members 30 are 15 then arranged in position for engagement with the rails 28 as shown in Fig. 2 of the drawings. One of the clamping members 31 is then applied in the manner heretofore explained, and the terminal hook 36 thereof 20 is engaged with the adjacent extremity of the member 37, it being observed that the said member is disposed to fulcrum substantially midway its ends upon the shoulders 17 and 18 which are accordingly provided with curved faces 20. The free extremity of the member 37 is then bent downwardly between the side walls of the tie and the opposite clamping member 31 is then engaged with the adjacent rail and 25 30 the arm 35 thereof is inserted between the adjacent end of the member 37 and the contiguous member 30, whence the hook 36 of the said arm is then engaged with the adjacent seat 38 of the said member. It will be 35 observed that when thus in position, the member 37 will be held substantially straight, the resilient action of the said member normally tending to force the arms 35 of the members 31 upwardly into engagement with the curved faces of the chairs 25 and with the flanges 33 of the members 30. As will be obvious, such action of the member 37 will cause the flanges 32 and 34 of the members 30 and 31 to firmly engage the 40 45 base flanges of the rails 28 to thus securely clamp the rails to the tie.

Attention is now called to the fact that a load passing over the rails 28 would tend to force the extremities of the tie downwardly against the road-bed and owing to the fact that the sections 13 and 14 of the tie are hingedly connected, consequent vertical movement of the tie will be permitted. However, it is to be noted that the member 50 55 37 is disposed to normally maintain the sections of the tie in alinement or in proper horizontal position and any load upon the rails 28 tending to depress the extremities of the tie will be communicated directly 60 to the said member which by its resilient action, will cushion the impact of the said load.

The tension of the member 37 can, of course, be determined upon experiment but 65 since the resilient action of the tie in cush-

ioning the load is entirely dependent upon the said member, it is preferable that the member be relatively heavy so as to normally exert a considerable tension upon the clamping members 31. It is to be noted 70 that in the provision of the clamping members 30 and 31 that the necessity of spikes or other similar type of fastening devices is obviated. At the points where the meeting ends of the contiguous rails 28 occur, 75 the said meeting ends may be arranged medially of the chairs 25 to be thus held in position by the members 30 and 31, thus obviating the necessity of fish plates.

It will thus be seen that I provide a 80 metallic tie which will be relatively light in construction but which will through the provision of the member 37, which is disposed to coact with the hingedly connected sections 13 and 14 of the tie, be possessed 85 of the resilient qualities in cushioning the load, found in the ordinary wooden tie. It will further be seen that in the provision of the member 37, the sections of the tie will be resiliently held in normal position while 90 the said members will also coact with the clamping members 30 and 31 to maintain the rails firmly seated upon the tie.

While I have illustrated and described the preferred embodiment of the invention, 95 still, it will be readily understood that the construction disclosed could readily be formed from suitable sheet metal without, in the slightest, departing from the spirit thereof as defined in the appended claims. 100 For instance, the bottom wall 11 of the tie could be formed with reversely arranged and longitudinally extending tongues at their confronting extremities. One of the 105 said tongues could then be rolled upon itself to receive the pivot pin 21 which could also be formed of suitable sheet metal, while the opposite tongue could be similarly rolled to loosely receive the free extremity of the pivot pin. In thus rolling the tongues and 110 providing a sheet metal pivot pin of a relatively large diameter, it will be clear that the rolled portions of the tongues will provide shoulders similar to the shoulders 17 and 18. Further, the chairs 25 could each 115 be formed from a length of suitable sheet metal provided at its extremities with reduced flanges or lugs disposed to engage over the side walls of the body of the tie, the intermediate portions of the piece of 120 metal forming the chair being rolled inwardly to provide the curved lower face 28' and the seat 29.

While I have shown the clamps 31 as being each provided with a terminal hook or 125 flange 36, still, the said clamps may be formed with a terminal flange or lip extending at substantially right angles to the portions 35 thereof and disposed to engage over the extremities of the locking 130

member 37 in which event, the terminal hooks formed on the said member would be eliminated.

Having thus described my invention, 5 what I claim and desire to secure by Letters Patent is:—

1. A railway tie including a body portion having its ends disposed for movement in a vertical plane, rail clamping members operatively engaging the tie, and a locking member engaging said clamping members and disposed to normally maintain the extremities of the tie in normal position. 10

2. A railway tie including a body portion having its extremities disposed for movement in a vertical plane, detachable rail clamping members operatively engaging the tie, and a locking member detachably engaging the tie and said rail clamping members, 20 said locking member being disposed to normally maintain the extremities of the tie in normal position.

3. A railway tie including a body portion having its extremities disposed for movement in a vertical plane, rail clamping members operatively engaging the tie, and a locking member fulcruming upon the tie and engaging said clamping members, said locking member being disposed to normally 25 maintain the extremities of the tie in normal position.

4. A railway tie including a body portion open upon one side and having its extremities disposed for movement in a vertical plane, rail clamping members operatively engaging the tie, and a combined closure and locking plate fitting within the open side of the tie and engaging said clamping members, said plate being disposed to normally 35 maintain the extremities of the tie in normal position.

5. A railway tie including a body portion formed of hingedly connected sections and provided with a shoulder, rail clamping members operatively engaging the tie, and a locking member seating upon said shoulder and engaging said clamping members, said locking member being disposed to normally 45 maintain the extremities of the tie in normal position.

6. A railway tie including a body portion formed in sections, one of said sections having a stud formed thereon disposed to engage within a suitable recess provided in the 55 opposite section whereby to hingedly connect the said sections, each of said sections having a shoulder formed thereon, rail clamping members operatively engaging the tie, and a resilient locking member seating upon said shoulders and engaging said 60

clamping members, said locking member being disposed to normally maintain the extremities of the tie in normal position.

7. A railway tie including a body portion having its extremities disposed for movement in a vertical plane, coacting rail clamping members arranged in pairs and operatively engaging the tie, one member of each pair being disposed to urge the other member of each of said pairs into operative 65 position, and a locking member engaging one member of each of said pairs, said locking member being disposed to normally maintain the extremities of the tie in normal position. 70

8. A railway tie including a body portion having its extremities disposed for movement in a vertical plane, coacting rail clamping members operatively engaging the tie, and a locking member engaging said 80 clamping members and disposed to normally maintain the extremities of the tie in normal position.

9. A railway tie including a body portion having its extremities disposed for movement in a vertical plane, said body portion being provided with rail chairs having seats formed therein, coacting clamping members arranged in pairs and operatively engaging said chairs, one clamping member of each 85 pair being disposed within the seat of the adjacent chair, and the other clamping member of each of said pairs being arranged to embrace the adjacent chair to operatively engage the said first mentioned clamping 90 member coacting therewith for urging said first mentioned member into operative position, and a locking member engaging the said last mentioned clamping members of each pair and disposed to normally maintain the extremities of the tie in normal 95 position. 100

10. A railway tie including a body portion having its extremities disposed for movement in a vertical plane, the said body portion being provided with rail chairs, resilient coacting rail clamping members embracing the said chairs, and a resilient locking member detachably and operatively engaging said clamping members, said locking member being disposed to normally maintain the extremities of the tie in normal 105 position. 110

In testimony whereof I affix my signature in presence of two witnesses.
